UNITED STATES PATENT OFFICE

OSCAR R. BARTH, OF DETROIT, MICHIGAN

MAGAZINE PENCIL

Application filed January 13, 1930. Serial No. 420,467.

The present invention relates to pencils and has for its principal object to provide a magazine pencil by means of which a plurality of varied colored leads may be carried within the pencil for selective positioning in the pencil.

A further object is to provide a pencil of this character in which the desired colored lead may be easily and quickly brought into writing position.

A further object is to provide a pencil which is simple and practical in construction, neat and attractive in appearance, efficient and reliable in performance and otherwise well adapted for the purposes for which the same is intended.

Other objects and advantages reside in the special construction, combination and arrangement of the various elements forming the invention as more fully hereinafter described and claimed, reference being had to the accompanying drawings forming part hereof, wherein like numerals refer to like parts throughout, and in which:

25 Figure 1 is a side elevational view,

Figure 2 is a longitudinal sectional view,

Figure 3 is a view in elevation of the lead guide for directing some of the sticks of lead into writing position,

30 Figure 4 is a similar view of the plug carried in the opposite end of the pencil,

Figures 5 to 9 inclusive are transverse sectional views taken respectively along the line 5—5, 6—6, 7—7, 8—8 and 9—9 of Figure 2,

35 and

Figure 10 is a group perspective view of one of the lead retaining sleeves and the ram rod for ejecting the lead from the sleeve.

Referring now to the drawings in detail 40 wherein for the purpose of illustration I have disclosed a preferred embodiment of the invention, the numeral 5 designates the barrel of the pencil which is of a hollow tubular construction and open at each end, one end of the barrel being threaded for receiving the threaded tapered end 6 which is also of hollow construction.

The opposite end of the barrel is fitted with 45 a plug 7 having a shoulder 8 formed thereon

engaging the end of the pencil to limit the inward movement of the plug.

In the end of the pencil opposite from the plug 7 is carried a lead guide 9 of substantially cylindrical formation and having a plurality of spring fingers 10 formed at one end for positioning within the tapered portion of the end 6.

The opposite end of the guide 9 is formed with a step 11 which extends longitudinally 55 of the barrel with its free end inserted in a bore 12 formed in the plug 7. The stem is secured to the plug for movement as a unit by a machine screw 13 threaded through an opening in the wall of the plug.

The plug and the guide are rotatably carried within the barrel and it will be apparent from the foregoing that upon the turning of the outer end of the plug that the guide will be likewise moved.

70 The inner ends of the plug 7 and the guide 9 are spaced apart as clearly shown in Figure 2 of the drawings and within the chamber thus provided is fitted a magazine 14 composed of a plurality of interconnected and 75 concentrically arranged tubes 15 having their inwardly disposed walls open and adapted for receiving sleeve 16 within which the lead 17 is carried.

The magazine 14 is snugly fitted within the 80 barrel so that the walls of the barrel will frictionally engage the tubes of the magazine to prevent idle rotation of the magazine within the barrel.

85 The guide 9 is formed at one side with a channel 18 of sufficient size to enable the sleeve 16 to move longitudinally through the guide when the channel 18 of the guide is in registry with the respective sleeves carried by the magazine. Accordingly by turning 90 the guide into a proper position and holding the pencil on end, with the guide 9 downwardly the sleeves carrying the lead will drop by gravitation through the guide so that the lead will protrude outwardly of the end 95 6 of the pencil.

The tapered end 6 of the pencil is threaded for threadedly receiving a cap 19, which is also tapered complementary to the tapered walls of the end 6. The walls of the end 100

are of relatively thin material and accordingly by threading the cap 19 upon the end the spring fingers 10 will be gripped about the side of the sleeve 16 and thus serve to secure the lead in proper position for writing.

The wall of the barrel, adjacent the end provided with the plug 7 is formed with a window 20, the portion of the plug adjacent the window is provided with an inscription sheet 21 which is wrapped about the plug and provided with suitable indicia 22 to indicate the various colors of the lead carried within the magazine 14.

Accordingly by placing the magazine in the barrel in a predetermined manner to coincide with the arrangement of the color identifying indicia on the plug and by the proper manipulation of the plug the desired colored lead will be brought into registry with the channel 18 for feeding into the writing end of the pencil.

In the outer end of the bore 12 of the plug is carried a ram rod 23 which may be utilized for forcing the lead 17 a suitable distance out of the sleeve 16 as the same is used.

It will be apparent that in order to eject the lead a desired distance that the ram rod and sleeve must be removed from the barrel

It is obvious that my invention is susceptible to various changes and modifications in construction without departing from the spirit of the invention or the scope of the appended claims, and I accordingly claim all such forms of the device to which I am entitled.

Having thus described my invention, what I claim as new is:

40. 1. A pencil comprising a barrel, a rotatable plug at one end, a rotatable clutch lead guide at its opposite end having an offset feed channel leading from said opposite end to one edge of the inward end, a rod connecting the plug and the guide for rotation as a unit, and a magazine positioned between the plug and the guide clutch and around the rod in the barrel adapted to position a plurality of lead holding tubes, each adapted to be released into the channel of said guide member when any one of said tubes comes into registry with the channel opening at the inner end thereof.

45. 2. A pencil comprising a barrel, a rotatable plug in one end thereof, a rotatable lead guide clutch on the other end, a rod connecting the plug and guide for rotation as a unit, and a magazine positioned between the plug and the guide and about the rod and having a plurality of chambers to accommodate a plurality of lead carrying tubes, said guide clutch comprising a cylindrical block one end of which is adapted to form a closure for the magazine, said block having an irregular conical recess in its other end, and an offset

lead receiving channel adapted to receive a tube of lead from the magazine, and spring fingers on the other end of the block adapted to engage a tube of lead and position it in said channel, said channel having communication with the said one end of the block and the other end thereof.

70. 3. A pencil comprising a barrel, a plug rotatably mounted in one end thereof, a lead guide rotatably mounted on the opposite end thereof, a rod connecting said guide with said plug for rotation as a unit, an offset channel in the guide communicating with the outer end of the guide and the inner ends thereof, lead gripping fingers carried by the guide, a magazine positioned in the barrel between the inner ends of the plug and of the guide, said magazine being composed of a plurality of open bottomed parallel lead holding tubes equally spaced from a common center and the inner end of said channel adapted to be selectively registered with the open bottoms of the tubes of the magazine and a tip threaded on the end of the barrel to confine said fingers, and a cap on the tip for adjustably compressing the tip and the fingers about the lead to hold the lead in writing position.

75. 4. In a pencil comprising a cylindrical barrel, a manually rotatable plug mounted in one end thereof, a rotatably mounted lead guide on the opposite end thereof, an offset lead receiving channel in said guide communicating with both ends of the guide, a rod carried by the inner end of the guide and secured in said plug whereby to fixedly connect said plug and guide in spaced relation for rotation as a unit, a plurality of lead gripping fingers carried at the outer end of the guide, a tapered tip carried by the end of the barrel forming a cover for the fingers, said tip having its outer end open, and a cap threaded on the small end of the tip for adjustably compressing the tip and the fingers, a magazine positioned between the plug and the guide and composed of a plurality of lead receiving chambers with which the inner end of the channel of the lead guide is adapted to be selectively registered, a window in the barrel to expose a portion of the plug, a colored strip encircling the said portion of the plug and visible through said window, lead identifying indicia on said strip adapted to indicate the position of the different magazine chambers as they are registered with the inner end of said channel in said guide.

80. 5. A pencil of the enclosed magazine type as described consisting of an open ended barrel internally screw threaded at one end to receive a hollow frusto-conical apertured tip and adapted to receive in its other end a rotatable plug which is operably connected by a centralized rod to a guide in the form of a cylinder having spring fingers arranged on one end bent to contact and conform to

the inner surface of the conical tip, a magazine frictionally retained against rotation by the walls of the barrel and between the inner ends of the plug and the lead guide and about 5 the rod consisting of a series of parallel open ended chambers arranged equidistantly from a common center and adapted to contain tubes of writing medium gravitationally dis-
10 chargable from the chambers into writing position in the tip through an offset channel in the lead guide leading from one side of its inner end and communicating with the aperture in the tip, and a screw cap on said tip for contracting the tip and said spring
15 fingers upon the tube of writing medium to adjustably retain the same, said plug adapted to be rotated in the barrel to register a selected magazine chamber with the inner end of the channel.

20 In testimony whereof I affix my signature.
OSCAR R. BARTH.
